UNITED STATES PATENT OFFICE

THOMAS W. MORRIS, OF CHICAGO, ILLINOIS

TRIMMING APPARATUS

Application filed July 22, 1929. Serial No. 380,135.

My invention relates to trimming apparatus and more specifically to apparatus for trimming the overflow from a molded rubber heel.

5 One of the objects of my invention is to provide apparatus of this character which will trim the overflow from the rubber heel with very little attention on the part of the operator.

10 A further object is to provide apparatus of this character which will automatically guide and direct the heel in such a way that the entire outline of the heel will be trimmed without any attention on the part of the operator.

15 A further object is to provide improved details of construction in apparatus of this character.

20 Further objects will appear from the description and claims.

In the drawings, in which an embodiment of my invention is shown—

Figure 1 is a perspective view of the apparatus for trimming a rubber heel;

25 Fig. 2 is a plan view, parts of the apparatus being in horizontal section;

Fig. 3 is a side elevational view of the cutters and associated parts;

30 Fig. 4 is a section on the line 4—4 of Fig. 3;

Fig. 5 is a section on the line 5—5 of Fig. 3;

Fig. 6 is a detailed view of the bracket for supporting the pressure roller;

35 Fig. 7 is a plan view of the construction employed for guiding the heel and for trimming the sides and rear edge; and

Fig. 8 is a section on the line 8—8 of Fig. 2.

Referring to the drawings in detail, the construction shown comprises a trimmer 1 having a pair of cooperating cutting discs 2 and 3 which draw the heel 4 towards the cutters, a pair of spring-pressure rollers 5 for engaging the upper surface of the heel to hold the heel down as it is being trimmed, a turntable 6 on which the heel is supported as it is being trimmed, pivotally mounted means 7 for guiding the heel as the cutters are acting on it so that the entire outline of the heel, with the exception of the breast 8, will be trimmed, said guide means comprising a roller 9 for engaging the untrimmed

side of the heel opposite the side on which the cutter initially acts, an abutment member 10 engaged by the breast of the heel forming a spring fulcrum about which the heel turns as the rear of the heel is being trimmed and a second abutment member 11 engaged by the trimmed side of the heel as the opposite side of the heel is being trimmed, a conveyor 12 for carrying the heel from said first trimmer, a second conveyor 13 running alongside said first conveyor, a guide and deflector member 14 above the first conveyor for deflecting the heel from the first conveyor to the second conveyor and causing the heel to be turned to present the breast portion in position for trimming, a second trimmer 15 for trimming the breast of the heel, similar in all respects to the first trimmer 1, adjustable guide means 16 above the second conveyor 13 for engaging the breast of the heel and steering it to the second trimmer, a pair of spring-pressure rollers 5 for engaging the upper side of the heel as the breast is being trimmed, and a spring-pressed roller guide 17 for engaging the end of the heel opposite the breast for holding the breast in proper relation to the trimmer.

Before describing in detail the construction, I will now briefly outline the operation. An operator places the heels 4 to be trimmed one-by-one in proper relation to be acted on by the first trimmer. The overflow 18 is seized between the edges of the two cutting discs 3 and 4 which trim the overflow close to the body of the heel, the spring-pressed roller 9 holding the body of the heel over against the edge of the upper cutting disc 2, as shown in Fig. 5. As the cutting discs draw the heel rearwardly the breast of the heel engages first the roller 9 and next the adjustable stop 10 on the pivoted guide member 7 as will be understood by referring to Fig. 7, the heel turning in a counterclockwise direction as viewed in this figure from the full-line to the dotted-line position, the pivoted guide member 7 in the meantime swinging from the full-line to the dotted-line position, about the pivotal point 19 against the action of the coil tension spring 20 which tends to hold the pivoted guide member in the full-

line position. The turntable 6 on which the heel rests facilitates this turning movement of the heel. As the heel turns, the trimmed side will come into engagement with the 5 serrated edge 21 of the adjustable abutment 11 and will thereafter engage the roller 22 on this abutment 11, parts being then substantially as shown in dotted lines in Fig. 7. In this position the trimmed rear edge of 10 the heel will be resting on the traveling conveyor 12 and the action of this traveling conveyor, together with the drawing action of the cutting discs, will cause the heel to be moved bodily rearward, the roller 22 facilitating this rearward movement, and the heel will finally be carried away on this traveling conveyor. A roller 23 is provided to engage the upper surface of the heel as it is traveling along on the conveyor to prevent 15 it from becoming improperly located and a pair of rollers 24 are provided, one on each side of the heel, to assist in keeping the heel in its proper position on the belt 12. As the heel travels rearwardly on the conveyor 20 the portion thereof opposite the breast portion comes into engagement with the inclined adjustable friction guide 14 which deflects the heel from the first conveyor over onto the second conveyor 13, this transfer at 25 the same time giving the heel a counterclockwise movement of rotation as viewed in Figs. 1 and 2 through about 90°, so that the heel comes into engagement with the roller guides 16 of the second trimmer 15, substantially as 30 shown in Fig. 1. Here the roller guides bring the overflow on the untrimmed breast of the heel into proper position to be engaged by the cutting edges of the two cutting discs 2 and 3 of the second trimmer and also 35 steering the heel back from the second conveyor 13 onto the first conveyor 12. The action of this conveyor, together with the drawing action of the cutting discs, causes the heel to move rearwardly between the upper cutting disc 2 and the spring-pressed guide rollers 25. These spring-pressed 40 guide rollers hold the breast of the heel over against the edge of the upper cutting disc 2 substantially as shown in Fig. 5 so that in 45 this operation the entire breast of the heel is trimmed. Thereafter the conveyor carries the completely trimmed heel rearwardly to the end of the conveyor from which it is discharged. 50

55 Coming now to a description of details of construction, the cutting discs themselves are in general of the type disclosed in my prior Patent No. 1,361,531 and will not be described in detail. They are driven in any suitable manner from a motor 26 by means 55 of belts 27, pulleys 28 and suitable intermediate transmission. I have found that the passage of the heel through the first trimmer is facilitated by the provision of a small 60 roller 29 just above the upper cutting disc 2

as shown in Figs. 3, 4 and 5, this roller being mounted on a bracket 30 which is adjustably mounted on a bar 31 secured to the bearing bracket 32 in which the cutter shaft 33 is mounted. This roller may be adjusted laterally by means of the two set screws 34 threaded through ears 35 on the bracket 30 and engaging the edges of the bar 31, the bracket being secured, when adjusted, by means of a clamping screw 36 extending through a slot 37 in the bracket 30 and threaded into the bar 31 as shown in Fig. 4. The roller may be adjusted vertically by means of the clamping screws 38 extending through slots 39 in the bar 31 and threaded into the bearing bracket 32 as shown in Fig. 3.

The turntable 6 on which the heel rests as it is being trimmed may be rotatably mounted in an opening 40 in the supporting table 41 and may be provided with an anti-friction bearing 42, as shown in Fig. 8, seated in a supporting bracket 43 secured to the under side of the table 41.

The series of rollers 44 for steering the heel in the proper position with respect to the cutting discs 2 and 3 may be mounted on a roller support 45 which is adjustable laterally by means of lock nuts 46 and a clamping screw 47, as shown in Fig. 2.

The pressure rollers 5 which engage the upper surface of the heel as it is being trimmed may be mounted on a horizontal extension 48 of a supporting post by means of the spring bracket construction shown in Fig. 6. Each roller is mounted in a forked bar 49 secured to a bearing bracket 50 rockably mounted on the horizontal post 48. The roller is pressed downwardly by means of a coil compression spring 51 seated in a spring barrel 52, one end of the spring engaging a plunger portion 53 on the bar 49 which fits loosely in the spring barrel. The other end of the spring is engaged by the end of a screw 54 threaded into the spring barrel by means of which the tension of the spring may be adjusted. The downward movement of the roller is limited by a stop screw 55 threaded into an arm 56 on the bracket 57, the point of this screw engaging the bar 49. This bracket 57 may be clamped on the horizontal post 48 by means of a clamping screw 58. By adjusting the screw 54, the desired spring pressure on the upper surface of the heel may be obtained and by adjusting the screw 55 the roller will be held at such a height when no heel is under the roller that when the next heel comes along it will readily pass underneath the roller and be properly held thereby.

The yieldable pivotally mounted guide means 7 comprises a support 59 pivotally mounted at 19, a coil tension spring 20, one end of which passes around a pulley member 60 secured to rock with the support 59

and the other end of which is secured to a pin 61, a stop member 62 on the rockable guide 59 for engagement with an adjustable stop screw 63, a roller 9 for engaging the untrimmed side of the heel as the heel is first presented to the cutters, an anti-friction roller 64 and an adjustable abutment member 10 for engaging the breast of the heel as the curved rear edge of the heel is being trimmed, 10 a serrated adjustable abutment member 21 for engaging the trimmed side of the heel as the opposite side of the heel is being trimmed and an anti-friction roller 22 mounted on this serrated abutment member to facilitate the 15 final movement of the heel as it is about to leave the trimmer. This serrated abutment is adjustable on the rockable support by means of a pair of clamping wing nuts 65 threaded into studs 66 extending through a 20 slot 67 in the abutment member and mounted on the rockable guide 59.

One of the anti-friction rollers 24 is adjustable by means of a wing nut 68 threaded onto a stud extending through a slot 69 in the 25 supporting bar 70 on which this roller is mounted.

In order to assist in keeping the heel in proper position, the roller 71 is provided adjacent the cutter 3, this roller being adjustable by means of a wing nut 72 threaded onto a stud extending through a slot 73 in the bracket 74 on which the roller 71 is mounted.

The inclined guide and deflector 14 is adjustably mounted by means of a wing nut 75 threaded on a stud extending through a slot 76 in the bar on which this deflector is mounted. The deflector may be covered with a suitable material which will have the desired 40 frictional qualities, such as soft leather or the like.

The series of guide rollers 77 for steering the heel into proper relation with respect to the cutters of the second trimmer may be mounted in the same manner as the rollers 45 44 for the first trimmer. The spring-pressed guide rollers 25 for holding the breast of the heel over against the cutter 2 may be mounted on a roller support 78 pivotally mounted at 50 79 on a rock bar 80 and held in adjusted position by means of a screw 81 extending through a slot 82 in the roller support 78. The rock bar 80 is held toward the cutters by means of a coil tension spring 83, the 55 bar being pivotally mounted at 84 and limited in its movement toward the cutters by means of an adjusting stop screw 85 threaded through a bracket 86 and having its point engaging the end of the rock bar 80. The rock bar 80 itself is adjustable from front 60 to rear by means of the wing nuts 87 threaded onto studs extending through a slot 88 in the base plate 89 on which the rock bar 80 is pivotally mounted.

65 The conveyors 12 and 13 are driven in any

suitable manner, the first conveyor 12 being shown as driven by a sprocket chain 90 from the shaft 91 of the vertical cutting disc 3 of the rear trimmer and the second conveyor belt 13 being shown as driven by belt 92 and 70 pulleys 93 from the shaft 94 of the vertical cutter 3 of the first trimmer.

I claim:

1. Apparatus for trimming the overflow from a rubber heel comprising a trimmer having rotating cutting edges which draw the work toward the cutters, a spring pressure roller for engaging the upper surface of the heel to hold the heel down as it is being trimmed, yieldable pivotally mounted means for guiding said heel as said cutters are acting on it so that the entire outline of the heel with the exception of the breast will be trimmed, said guide means comprising a roller for engaging the untrimmed side of the heel opposite the side on which the cutter initially acts, an abutment member engaged by the breast of the heel forming a spring fulcrum about which the heel turns as the rear of the heel is being trimmed, and a second 90 abutment member engaged by the trimmed side of the heel as the opposite side of the heel is being trimmed, a turntable for supporting the heel as it is being acted on by said trimmer, a conveyor for carrying said heel from said guide and trimming means, a second conveyor running alongside said first conveyor, guiding and deflecting means above said first conveyor for deflecting the heel from said first conveyor to said second conveyor and causing the heel to be turned to present the breast portion in position for trimming, said deflector comprising a frictional abutment engaged by the heel extending obliquely to the first conveyor, a second 100 trimmer for trimming the breast of the heel, adjustable guide means above the second conveyor for engaging the breast of the heel and steering it to the trimmer, a spring pressure roller for engaging the upper surface of the heel as it is being trimmed to hold the heel down on the conveyor, and a spring-pressure roller for engaging the end of the heel opposite the breast for holding the breast of the heel in proper relation to the trimmer. 110

2. Apparatus for trimming the overflow from a rubber heel comprising a trimmer, means for guiding said heel so that the entire outline of the heel with the exception of the breast will be trimmed, a second trimmer for trimming the breast of the heel, means for guiding said heel so that the breast will be trimmed, and means for conveying the heel from the first trimmer to the second trimmer. 120

3. Apparatus for trimming the overflow from a rubber heel comprising a trimmer, and means for guiding said heel so that the entire outline of the heel with the exception 130

- of the breast will be trimmed, said trimmer having rotating cutting edges which draw the work toward the cutters, and said guiding means comprising yieldable pivotally mounted means for guiding said heel as said cutters are acting on it, a roller for engaging the untrimmed side of the heel opposite the side on which the cutter initially acts, an abutment member engaged by the breast of the heel forming a spring fulcrum about which the heel turns as the rear of the heel is being trimmed, and a second abutment member engaged by the trimmed side of the heel as the opposite side of the heel is being trimmed.
- 15 4. Apparatus for trimming the overflow form a rubber heel comprising a trimmer, and means for guiding said heel so that the entire outline of the heel with the exception of the breast will be trimmed, a conveyor for carrying said heel from said guide and trimming means, a second conveyor running alongside said first conveyor, guiding and deflecting means above said first conveyor for deflecting the heel from said first conveyor to said second conveyor and causing the heel to be turned to present the breast portion in position for trimming, said deflector comprising a frictional abutment engaged by the heel extending obliquely to the first conveyor, and a second trimmer for trimming the breast of the heel.
- 20 5. A rubber heel trimming apparatus comprising rotatable trimming knives which draw the work forward as they cut, and means for controlling the heel in its movement comprising a yielding pressure member alongside which the side edge of the heel travels in its movement, said pressure member being engageable with the untrimmed side edge of the heel opposite the side on which the trimming knives initially act for pressing the heel toward the knives.
- 25 6. A rubber heel trimming apparatus comprising rotatable trimming knives which draw the work forward as they cut, and means for controlling the heel in its movement comprising a pivotally mounted yielding pressure member alongside which the side edge of the heel travels in its movement, said pressure member being engageable with the untrimmed side edge of the heel opposite the side on which the trimming knives initially act for pressing the heel toward the knives.
- 30 7. A rubber heel trimming apparatus comprising rotatable trimming knives which draw the work forward as they cut, and means for controlling the heel in its movement comprising an anti-friction yielding pressure member alongside which the side edge of the heel travels in its movement, said pressure member being engageable with the untrimmed side edge of the heel opposite the side on which the trimming knives initially act for pressing the heel toward the knives.
- 35 8. A rubber heel trimming apparatus com-

prising rotatable trimming knives which draw the work forward as they cut, and means for controlling the heel in its movement comprising a pivotally mounted anti-friction pressure member alongside which the side edge of the heel travels in its movement, said pressure member being engageable with the untrimmed side edge of the heel opposite the side on which the trimming knives initially act for pressing the heel toward the knives.

9. A rubber heel trimming apparatus comprising rotatable trimming knives which draw the work forward as they cut, and means for controlling the heel in its movement comprising a yieldable swinging fulcrum member engageable with the breast edge of the heel in its movement about which fulcrum the heel swings, said fulcrum member swinging to accommodate itself with the movement of the heel.

10. A rubber heel trimming apparatus comprising rotatable trimming knives which draw the work forward as they cut, and means for controlling the heel in its movement comprising a yieldable swinging member provided with a yielding pressure member alongside which the side edge of the heel travels in its movement, said pressure member being engageable with the untrimmed side edge of the heel opposite the side on which the trimming knives initially act for pressing the heel toward the knives, and said swinging member being also provided with a fulcrum member engageable with the breast edge of the heel in its movement about which fulcrum the heel swings, said fulcrum member swinging to accommodate itself to the movement of the heel.

11. A rubber heel trimming apparatus comprising rotatable trimming knives which draw the work forward as they cut, and means for controlling the heel in its movement comprising a yieldable swinging member provided with a yielding pressure member alongside which the side edge of the heel travels in its movement, said pressure member being engageable with the untrimmed side edge of the heel opposite the side on which the trimming knives initially act for pressing the heel toward the knives, and said swinging member being also provided with a fulcrum member engageable with the breast edge of the heel in its movement about which fulcrum the heel swings, said fulcrum member swinging to accommodate itself to the movement of the heel, and anti-friction means engaging the under face of the heel in its movement.

12. A machine for trimming articles of non-circular periphery, said machine comprising a turntable for supporting the work, a rotary cutter at one side thereof adapted to trim and advance the work, conveyor means adjacent the turntable, in such rela-

tion thereto as to partially underlie the article at the conclusion of the trimming thereof, for removing the work from the turntable at the conclusion of the trimming operation, 5 and yielding means adapted to be positioned by the contour of the article during the trimming operation for assisting the cutter in effecting movement of the work from the turntable onto the conveyor.

10 13. Apparatus for trimming the overflow from a rubber heel, said apparatus comprising a trimmer, a turntable adjacent the trimmer for supporting a heel to be trimmed, means for guiding said heel so that the entire 15 outline of the heel with the exception of the breast will be trimmed, a second trimmer for trimming the breast of the heel, means for guiding said heel so that the breast will be trimmed, and means for conveying the 20 heel from the first trimmer to the second trimmer.

14. Apparatus for trimming the overflow from a rubber heel, said apparatus comprising a trimmer, a turntable adjacent the trimmer for supporting a heel to be trimmed, means for guiding said heel so that the entire 25 outline of the heel with the exception of the breast will be trimmed, a conveyor for carrying said heel from said guide and trimming 30 means, a second conveyor running alongside said first conveyor, guiding and deflecting means above the first conveyor for deflecting the heel from said first conveyor to said second conveyor and causing the heel to be 35 turned to present the breast portion in position for trimming, said deflector comprising a frictional abutment engaged by the heel extending obliquely to the first conveyor, and a second trimmer for trimming the breast 40 of the heel.

15. In a heel-trimming machine, the combination of a support for a heel to be trimmed, a rotary cutting adapted to apply a peripheral impelling force to the margin 45 of a heel as it trims the same, yielding means engaging the heel at the opposite side thereof from the cutter adapted normally to resist forward feeding of the work and causing the latter to rotate under the impelling force, 50 and a roller bearing against the upper face of the heel between the cutter and the axis of rotation of the heel.

16. In a heel-trimming machine, the combination of a support for a heel to be 55 trimmed, a rotary cutter adapted to apply a peripheral impelling force to the margin of a heel as it trims the same, means urging the heel toward the cutter and causing it to rotate under the impelling force, and a pair 60 of rollers engaging the upper face of the heel at opposite sides of its axis of rotation.

17. Apparatus for trimming the overflow 65 from a rubber heel, said apparatus comprising a trimmer, means including a turntable support for the heel and a hold-down roller

engaging the upper face of the heel for guiding said heel so that the entire outline of the heel with the exception of the breast will be trimmed, a second trimmer for trimming the breast of the heel, means for guiding said heel so that the breast will be trimmed, and means for conveying the heel from the first trimmer to the second trimmer. 70

18. Apparatus for trimming the overflow from a rubber heel, said apparatus comprising a trimmer, means for maintaining a heel in operative relation to the trimmer while trimming the overflow therefrom around a part of the periphery of the heel, a second trimmer for continuing the trimming of the heel, and means for conveying the heel from the first trimmer to the second trimmer. 75 80

In witness whereof, I have hereunto subscribed my name.
